UNITED STATES PATENT OFFICE

NEVIN SEASHOLTZ FOCHT, OF POTTSTOWN, PENNSYLVANIA

SOUND-REPRODUCING DIAPHRAGM

Application filed April 13, 1927. Serial No. 183,511.

This invention relates to sound reproducing diaphragms adapted for use in connection with talking machine reproducers or radio loud speaker units.

5 While it has been heretofore proposed to use diaphragms made of different materials and different shape, nevertheless the general practice until recently was to use a mica diaphragm which, although satisfactory to 10 a degree, nevertheless did not respond to the wave frequencies of different notes in such a way that the sounds audible to the normal ear were accurately and faithfully reproduced. That condition was largely due to 15 the fact that the stiffness of the diaphragm made it more sensitive to sounds of high pitch or frequency than the sounds of low pitch and consequently many of the low sounds or musical notes were lost. Or, on the other 20 hand if a very flexible diaphragm was used the reproduction of the high notes suffered while the low sound or notes were more pleasingly rendered. Therefore, considering the 25 past difficulty of meeting both the requirements of stiffness and flexibility in one and the same diaphragm, experiments have been made where several diaphragms have been used, each diaphragm being sensitive or responsive to vibrations of certain frequencies, 30 that is, sensitive to a specified range of vibrations. While this has been found practical in some cases, more especially in radio amplifiers, nevertheless it is not practical for the general run of talking machines or loud 35 speakers where it is desirable to have a small unit which may be embodied in the limited space of an ordinary talking machine reproducer frame, or within the casing of a loud speaker of the type generally used in connection 40 with household radio receiving sets.

Accordingly, one of the primary objects of the present invention is to provide a novel diaphragm having the capacity to more accurately reproduce sounds or notes of both 45 high frequency and low frequency trans-

mitted thereto by a suitable energizer such for example as the needle arm of a talking machine reproducer or the vibrating armature of an electrical unit of a radio loud speaker. In that connection it is proposed 50 to provide a diaphragm so constructed that the entire diaphragm will readily respond to low notes or sound waves of low frequency while other parts thereof will respond to high 55 notes or sound waves of higher frequency.

A further object of the invention is to provide a single diaphragm embodying a plurality of smaller diaphragms arranged eccentrically with reference to the axis of the main diaphragm thereby not to hinder the 60 functioning of the diaphragm as a whole.

With the above and other objects in view which will more readily appear as the nature of the invention is better understood, the same consists in the novel construction, 65 combination and arrangement of parts hereinafter more fully described, illustrated and claimed.

A preferred and practical embodiment of the invention is shown in the accompanying 70 drawings in which

Fig. 1 is a plan view of the improved diaphragm.

Fig. 2 is a cross sectional view taken on the line 2—2 of Fig. 1.

Fig. 3 is a cross sectional view taken on the line 3—3 of Fig. 1.

Fig. 4 is a cross sectional view taken on the line 4—4 of Fig. 1.

Fig. 5 is a side elevation partly in section of a standard electrical loud speaker unit showing the application of the present diaphragm thereto.

Fig. 6 is an elevation of a talking machine reproducer embodying the diaphragm of Fig. 1.

Fig. 7 is a detail view illustrating the manner of attaching the arm to the distributing member.

Fig. 8 is an edge elevation of a talking ma.

chine reproducer illustrating a modified means for attaching the distributing member to the diaphragm.

Fig. 9 is a detail sectional view illustrating the manner in which the circular groove permits main diaphragm to flex.

Similar reference characters designate corresponding parts throughout the several figures of the drawings.

10 In carrying the present invention into effect it is proposed to provide a diaphragm made of a material and embodying structural features and characteristics that will enable it to respond more accurately to the 15 frequency of vibration of both high and low notes, thereby causing a more faithful reproduction of the sounds than is possible with a diaphragm capable of functioning only to a more or less restricted frequency of 20 vibration as for example, a single flat diaphragm of uniform thickness throughout.

Therefore, according to the present invention it is proposed to incorporate in a single diaphragm the feature of sufficient flexibility 25 to permit of accurate reproduction of low notes as well as sufficient stiffness to reproduce faithfully the high notes or sounds of 30 high frequency while all parts of the diaphragm are responsive to the same source of energy.

Referring to the drawings, it will be observed that the diaphragm designated generally as A consists of a circular disk of any suitable and convenient material, preferably 35 duraluminum, or its equivalent, which constitutes the body of the diaphragm. The flexibility of the diaphragm from the axis B to the periphery C is maintained notwithstanding the fact that it is provided with the 40 relatively stiffer eccentrically located conical portions D, E and F due to the provision of the radially disposed hinging or flexing channels 1 which produce grooves at the face of the diaphragm and ribs at the back, said 45 channels communicating with the circular groove 1^a. These channels are of tapering formation having their wide ends at the axis of the diaphragm and their narrow ends opening into the circular flexing groove 1^a 50 adjacent the periphery C of said diaphragm. The said groove 1^a is spaced from the periphery of the diaphragm thereby leaving a flat marginal portion 2 to be engaged by the gasket means for holding the diaphragm in 55 the reproducer frame. This combination of flexing channels and the flexing groove enables the diaphragm A to flex from its axis to the point where it is gripped or engaged by the gasket so that under the force of pulsations of low frequency vibrations it will readily respond to and faithfully reproduce low or deep sounds, that is sounds of low frequency.

Between the flexing channels 1 the body 60 of the diaphragm is provided with the afore-

said conical portions which constitute a plurality of substantially conical subdiaphragms. These diaphragms are pressed out of the main body A so that the tips of the conical portions project outwardly from the face of the diaphragm to provide the apices 3, 4 and 70 5. The bases of the conical members D, E and F are not entirely circular as will be observed from Fig. 1 but are distorted at the side adjacent the periphery C of the disk to provide the straight intersecting sides x and y, resulting in the formation of a flexing rib z 75 extending from the apex of the cone toward the junction of the base lines x and y, and just touching the inside of the main circular flexing groove 1^a.

The effect of the cones D, E and F is to provide a plurality of relatively stiff subdiaphragms in the main diaphragm which is of relatively greater flexibility due to the provision of the flexing channels 1. The formation of the ribs z permits of sufficient flexibility in the conical portions to enable the sound vibrations of higher frequency to be transmitted to the cones to be assimilated with the slower vibrations or vibrations of low frequency imparted to the diaphragm as a whole. Yet, on the other hand, each cone D, E and F presents sufficient inherent stiffness to more faithfully reproduce the sound 90 vibrations of high frequency and short wave length.

As above explained, the outer end or tip of the flexing ribs z extend to and touch the inside of the main circular flexing groove 1^a 100 and thereby enable each cone to assimilate and synchronize the vibrations transmitted to it with the vibrations of the main diaphragm, and also assist in preventing the localization of strains on the cone in a line at right angles to the rib located substantially at the apex of the cone. If each cone had a circular base, the strains and stresses incident to the vibrations transmitted thereto would have a tendency to localize such strains in a way that would be harmful to the reproduction of all frequencies of audible sounds, but by forming the conical members in the manner indicated the main diaphragm A will be able to respond better to its tuned frequencies by 110 reason of the fact that the radially disposed flexing channels will permit maximum flexing of the main diaphragm from a substantially marginal point located in the main sound groove 1^a between the tips of the ribs z. 115 That is to say, the main circular groove 1^a between the tips of the ribs z will have the capacity to open and close under the influence of vibrations transmitted to the main diaphragm in cooperation with the radial flexing channels 1.

As previously indicated, the axes of the conical members D, E and F are arranged eccentrically to the axis of the main diaphragm A thereby to permit each cone to re- 120 125 130

ceive and transmit the vibrations of the frequency best adapted to its flexibility.

Also, in its preferred form, the conical members D, E and F are made of different thickness. For example, the conical member D is of slightly greater thickness at the apex 3 than at its base, while the conical members E and F are made with their apical portions 4 and 5 of progressively increasing thickness as will be observed from Figs. 3 and 4. It will of course be understood that in these views the thickness of the metal is somewhat exaggerated for sake of clearness but they will serve to illustrate the idea of providing a plurality of conical members whose walls are of different thickness thereby to give to the several members different degrees of stiffness which will enable each conical member to more readily receive and translate sound waves of varying frequency.

Each of the apices 3, 4 and 5 of the conical members D, E and F is connected with a vibration transmitting and distributing member 6 which performs substantially the functions of a plunger in transmitting to the diaphragm energy produced either by a needle arm when the device is used in a talking machine or the armature of a magnetic device when used as a loud speaker. The distributing member 6 is preferably of spider-like formation having radially disposed arms 7 which may be directly connected to the apices 3, 4 and 5 as shown in Figs. 5 and 6; or, on the other hand, as shown in Fig. 8 the said arms 7 may be connected to the apices by the posts or pins 8. The function of the arms 7 is to distribute to each of the sub-diaphragms a fixed band of wave frequency corresponding to the particular sub-diaphragm to which they are attached. That is to say, the distributing member 6 has its arm or prongs tuned to different frequencies and when it receives sound energy, said energy works off through its proper arm to the sub-diaphragm to which it is tuned. In the diaphragm shown in the drawings the sub-diaphragms D, E and F reproduce frequencies from 1,000 to 21,000 vibrations per second, each cone assuming its quota of that range of frequency to which it is tuned, while the entire diaphragm or main body is responsive to frequencies below 1,000 vibrations per second. The cones or sub-diaphragms therefore translate wave motion occurring in frequency from approximately 1,000 to 21,000 vibrations per second while the main body of the diaphragm translates the plunger action which manifests itself in frequencies of below 1,000 vibrations per second.

In Fig. 5 which illustrates the application of the invention to a radio loud speaker unit, utilizing a standard electrical device, the vibrating armature 9 is connected to the distributing member 6 by means of the link 10. This link in turn is connected to the armature

through the medium of a cushioning member 11, said member being preferably of rubber or equivalent material.

When the diaphragm is used in a talking machine reproducer as shown in Figs. 6, 7 and 8 the distributing member 6 is connected to the needle arm 12 through the medium of a bail or loop 13 carried by the member 6 which is surrounded by a rubber or equivalent gasket or washer 14. In this case one end of the needle arm 12 is bent around the gasket. In both constructions, therefore, the vibrations are transmitted to the diaphragm through a cushioning medium which prevents transmission of metallic sounds to the diaphragm but imparts the full strength of the vibration impulses thereto.

From the foregoing it will be apparent that the novel and distinctive feature of the present invention resides in the provision of a single diaphragm embodying in effect a plurality of diaphragms each having the property of assimilating the transmitting sounds best adapted to it, thereby enabling the reproducer to respond to a wider range of sound frequency and increasing its sensitivity while at the same time augmenting the volume of the sounds reproduced thereby and giving to each sound its more natural tone because of the fact that it is reproduced by means susceptible of flexing and effectually transmitting the frequency to which it is best adapted.

Without further description it is thought that the features and advantages of the invention will be readily apparent to those skilled in the art, and it will of course be understood that changes in the form, proportion, and minor details of construction may be resorted to, without departing from the spirit of the invention and scope of the appended claims.

I claim:—

1. A sound reproducing diaphragm including a main flexing body and a plurality of substantially conical sub-diaphragms arranged eccentrically to the axis of the main flexing body, and means for transmitting energy to the main flexing body and each of the sub-diaphragms.

2. A sound reproducing diaphragm including a main flexing body and a plurality of substantially conical sub-diaphragms of differential thickness and arranged eccentrically to the axis of the main diaphragm, and means for transmitting energy to the main flexing body and each of the sub-diaphragms.

3. A sound reproducing diaphragm including a body having a plurality of radially disposed flexing channels, and substantially conical sub-diaphragms formed from the body between said channels, and means for transmitting energy to said body and to said sub-diaphragms.

4. A sound reproducing diaphragm including a body having radially disposed flexing channels therein, a plurality of substantially conical sub-diaphragms formed from said body and providing apical portions arranged eccentrically with reference to the axis of the main body, and a vibration distributing member connected to said apical portions of the cones.
5. A sound reproducing diaphragm including a body having a plurality of tapering flexing channels, the wide ends of said flexing channels being arranged adjacent the axis of the body, and substantially conical sub-diaphragms formed from the body between said flexing channels, and a vibration transmitting and distributing member connected to each of the sub-diaphragms.
6. A sound reproducing diaphragm including a body having a plurality of tapering flexing channels, the wide ends of said flexing channels being arranged adjacent the axis of the body, and substantially conical sub-diaphragms formed from the body between said flexing channels, said sub-diaphragms being provided with a flexing rib lying radially with reference to the axis of the main diaphragm.
7. A sound reproducing diaphragm including a body having a portion thereof eccentric to its axis pressed into the form of a cone to provide a sub-diaphragm responsive to sound vibrations of different frequencies from the main diaphragm.
8. A sound reproducing diaphragm including a body having portions thereof pressed into substantially conical formation to provide a plurality of sub-diaphragms responsive to sound vibrations of different frequencies from the main diaphragm.
9. A sound reproducing diaphragm including a body having a main flexing groove and a plurality of tapering flexing channels communicating therewith, and substantially conical sub-diaphragms formed from the body between said flexing channels.
10. A sound reproducing diaphragm including a body having a circular main flexing groove adjacent the periphery thereof and flexing channels disposed radially with reference to the axis of the main diaphragm and communicating with said main flexing groove, and substantially conical sub-diaphragms formed from the body between said flexing channels.
11. A sound reproducing diaphragm including a body having a circular main flexing groove adjacent the periphery thereof and flexing channels disposed radially with reference to the axis of the main diaphragm and communicating with said main flexing groove, and substantially conical sub-diaphragms formed from the body between said flexing channels, and each of said sub-diaphragms being formed with a rib extending from the apex of the sub-diaphragm to the inner edge of said main flexing groove.
12. A sound reproducing means comprising a diaphragm including a body embracing within the peripheral edges thereof a plurality of integral areas responsive to sound vibrations of different frequencies, and means for connecting said areas with a source of energy.
13. A sound reproducing diaphragm, including a body embracing within the peripheral edges thereof a plurality of substantially conical sub-diaphragms, each having a rib portion directed toward the peripheral edge of the body of the diaphragm, and means for transmitting sound produced energy to the apices of the said substantially conical portions.
14. A sound reproducing diaphragm, including a body responsive to sound vibrations within a given range and having portions of said body responsive to wave bands of different frequency, and means for transmitting sound produced energy to said diaphragm whereby sounds of low frequency are translated by movement of the entire diaphragm while sounds of higher frequency are translated by said portions of the diaphragm responsive to wave bands of different frequency.
15. A sound reproducing diaphragm, including a body having a plurality of sub-diaphragms each adapted to be connected with a source of energy, and each diaphragm being responsive to a definite wave band of sound frequency.
16. A sound reproducing diaphragm, including a body having a plurality of sub-diaphragms each adapted to be connected with a source of energy, and said sub-diaphragms being responsive to different wave bands from 1,000 to 21,000 vibrations per second.
17. A sound reproducing diaphragm, including a body having a plurality of sub-diaphragms each adapted to be connected with a source of energy, and said sub-diaphragms being responsive to different wave bands from 1,000 to 21,000 vibrations per second, and the main body of the diaphragm being responsive to vibrations below 1,000 per second.
18. A sound reproducing diaphragm including a body portion responsive to sound vibrations within a given range of frequency, and portions of said body being formed to provide sub-diaphragms also responsive to sound vibrations of different frequencies within a given range, said range being different from the range of sound vibrations to which the body of the diaphragm is responsive, and means for transmitting sound produced energy to each of the sub-diaphragms and to the body of the diaphragm.
19. A sound reproducing diaphragm including a main flexing body and a plurality of

sub-diaphragms arranged eccentrically to the axis of the main flexing body, and means for transmitting sound produced energy to each of the sub-diaphragms and to the body of the diaphragm.

5 20. A sound reproducing diaphragm including a body portion having a plurality of sub-diaphragms formed integrally therewith and arranged eccentrically to the axis of the body of the diaphragm.

10 In testimony whereof I hereunto affix my signature.
